(57) **CLAIM**

The ornamental design for the concrete rake, as shown and described.

DESCRIPTION

FIG. 1 is a front perspective view of the concrete rake invention;

FIG. 2 is a front view of the concrete rake invention;

FIG. 3 is a back view of the concrete rake invention;

FIG. 4 is a right-side view of the concrete rake invention;

FIG. 5 is a left-side view of the concrete rake invention;

FIG. 6 is a top view of the concrete rake invention;

FIG. 7 is a bottom view of the concrete rake invention; and,

FIG. 8 is a rear perspective view of the concrete rake invention.
Structure that is not part of the claimed design but is considered necessary to show the environment in which the design is associated, is represented in the drawings by broken lines.
